US00D990597S

(12) **United States Design Patent** (10) Patent No.: **US D990,597 S**
(45) Date of Patent: **** Jun. 27, 2023**

(54) **GOLF CLUB HEAD**

(71) Applicant: **KARSTEN MANUFACTURING CORPORATION**, Phoenix, AZ (US)

(72) Inventors: **Cory S. Bacon**, Cave Creek, AZ (US);
David A. Higdon, Cave Creek, AZ (US)

(73) Assignee: **Karsten Manufacturing Corporation**, Phoenix, AZ (US)

(**) Term: **15 Years**

(21) Appl. No.: **29/799,872**

(22) Filed: **Jul. 16, 2021**

(51) LOC (14) Cl. **21-02**

(52) U.S. Cl.

USPC **D21/752**

(58) **Field of Classification Search**

(57) **CLAIM**

The ornamental design for a golf club head, as shown and described.

DESCRIPTION

FIG. 1 is a top perspective view of a golf club head; FIG. 2 is a bottom perspective view of the golf club head of FIG. 1;

FIG. 3 is a top view of the golf club head of FIG. 1;

FIG. 4 is a bottom view of the golf club head of FIG. 1;

FIG. 5 is a front view of the golf club head of FIG. 1;

FIG. 6 is a rear view of the golf club head of FIG. 1;

FIG. 7 is a heel side view of the golf club head of FIG. 1; and,

FIG. 8 is a toe side view of the golf club head of FIG. 1. The broken lines shown on the drawing figures form no part of the claimed design.

1 Claim, 7 Drawing Sheets
